INFANT'S CAR SEAT

Robert Martin Prashker, Kingston, Pa., assignor to
Jamy, Inc., Kingston, Pa.

Filed Apr. 6, 1970, Ser. No. 22,283

Term of patent 14 years

Int. Cl. D6—82

U.S. Cl. D15—1

FIG. 1 is a front elevational view of an infant's car seat or similar article showing my new design;

FIG. 2 is a side elevational view thereof;

FIG. 3 is a rear elevational view thereof; and

FIG. 4 is a section on the line 4—4 of FIG. 2.

I claim:

The ornamental design for an infant's car seat, as shown.
